DESIGN FOR A WATCH BRACELET OR SIMILAR ARTICLE

Jacques Kreisler, New Rochelle, N. Y., assignor to Jacques Kreisler Sales Corporation, New York, N. Y.

Application January 28, 1936, Serial No. 60,854

Term of patent 3½ years

To all whom it may concern:

Be it known that I, Jacques Kreisler, a citizen of the United States, residing at 243 Broadview Avenue, New Rochelle, New York, have invented a new, original, and ornamental Design for a Watch Bracelet or Similar Article, of which the following is a specification, reference being had to the accompanying drawing, forming a part thereof.

Figure 1 is a front elevational view of a watch
bracelet showing my new design.

Fig. 2 is a section on an enlarged scale on line
2—2 of Figure 1.

Fig. 3 is a section on an enlarged scale on line
3—3 of Figure 1.

I claim:

The ornamental design for a watch bracelet or similar article, as shown.

JACQUES KREISLER.
